United States Patent Office

Des. 208,805
Patented Oct. 3, 1967

208,805

MIXER

Dominic J. De Fano, Palatine, Robert O. Ernest, Oak Park, and Robert I. Kallman, Elburn, Ill., assignors to Sunbeam Corporation, Chicago, Ill., a corporation of Illinois

Filed Mar. 1, 1967, Ser. No. 6,013

Term of patent 14 years

(Cl. D44—1)

Fig. 3.

Fig. 4.

Fig. 5.

Fig. 6.

FIG. 1 is a perspective view of a mixer showing our new design;

FIG. 2 is a side elevation view of the mixer;

FIG. 3 is a top view thereof;

FIG. 4 is a front view thereof;

FIG. 5 is a rear view thereof; and

FIG. 6 is a bottom view thereof.

The essential features of the design are shown in full lines, with the base and standard being omitted from FIGS. 2-6 for convenience of illustration.

We claim:

The ornamental design for a mixer, as shown and described.
